UNITED STATES PATENT OFFICE.

CLAUD H. FOSTER, OF CLEVELAND, OHIO.

SIGNALING MECHANISM.

1,031,993.

Specification of Letters Patent. Patented July 9, 1912.

Application filed November 3, 1909. Serial No. 525,992.

To all whom it may concern:

Be it known that I, CLAUD H. FOSTER, a citizen of the United States, residing at Cleveland, in the county of Cuyahoga and State of Ohio, have invented a certain new and useful Improvement in Signaling Mechanisms, of which the following is a full, clear, and exact description, reference being had to the accompanying drawings.

10 This invention relates to wind instruments, and more particularly to instruments which may be employed with vehicles, such as automobiles, and operated by the pressure of a fluid, as the exhaust of the engines of such vehicles, to sound an alarm.

The objects of the present invention are to provide an instrument of this kind comprising a plurality of individual sounding or signaling members, each being provided 20 with an independent valve for supplying and cutting off the flow of pressure fluid thereto; also to provide an instrument of this kind with convenient and efficient means for operating such valves; also to provide 25 an instrument of this kind with efficient means whereby the members may be operated individually and whereby different groups of said members may be selected and simultaneously operated to produce signals 30 or musical chords.

With the above objects in view, the invention may be further defined as consisting of the combinations of elements embodied in the claims hereto annexed and illustrated 35 in the drawings forming a part hereof, wherein—

Figure 1 represents a side elevation of a portion of an automobile having my invention applied thereto; Fig. 2 is a detail in 40 perspective of the key board and operating means for sounding various groups of horns; Fig. 3 is a transverse sectional view of the key board shown in Fig. 2; and Figs. 4 and 5 are details of one of the valves which control the flow of pressure fluid to the signaling members.

In the embodiment of my invention shown herein, there are employed as signaling members a plurality of horns of the type 50 known to the trade as "Gabriel" horns,—that is to say, horns which are adapted to give a musical sound and to hold their pitch irrespective of wide variations in the pressure of the fluid by which they may be 55 operated. To each of these horns is connected a branch pipe or connection leading

from a common manifold or header, and each branch pipe or connection is provided with a valve having a wire or other suitable flexible connection extending therefrom to 60 a key board which is located alongside of the seat of the operator.

In the drawings, 1 represents, more or less conventionally, the body of an automobile, 2 the front fender and 3 the seat thereof. 65

4 denotes a pipe projecting through the side of the vehicle and connected to the engine exhaust 4^a. This pipe and the engine exhaust pipe will be provided with a cut-out valve, preferably such as shown in my 70 Patent #913,632, issued February 23, 1909, the stem of said valve being shown at 4^b and its casing at 4^c. The outer end of the pipe 4 communicates with the header 5, which is provided with a plurality of branch connections 6, each connected to the inlet end of a horn 7. Any suitable number of horns 75 may be connected to this header. Six such horns are shown in the drawing, but groups comprising various numbers of horns may 80 be employed, for instance, four, or ten. The header and horns are shown as located above the fender 2, but the position in which the horns will be placed may be varied to suit the convenience of the operator and the particular construction of the automobile with 85 which they may be employed.

Each branch connection 6 is provided with a valve, preferably of the type shown in Figs. 4 and 5. Referring more particularly to these figures, it will be seen that each branch is provided with oppositely located stop shoulders 8 and 9, preferably cast therewith. 10 denotes a valve stem which extends through the branch connection 6, 95 having its lower end journaled in a projection 11 from such branch. This stem is provided with a slot for the reception of a disk 12, the disk being secured in place by means of a suitable number of screws 13. At its upper end the stem is provided with 100 an operating disk 14, said disk having a series of apertures 15 adjacent to the periphery thereof, for the reception of a screw or pin 16. 17 denotes a stop projecting from the upper end of the valve stem beneath the disk 14 and adapted to engage the stop shoulders 8 and 9. 18 denotes a screw connecting the disk to the stop 17 and thus 110 to the valve stem and also serving as a means for connecting a spiral spring 19 to the valve stem and as a means for adjustably

connecting the valve to the key board. One end of the spring is connected to the lower end of the screw 18 and its opposite end to the stop shoulder 9. The parts are so arranged that, when the stop 17 is in engagement with the shoulder 9, the valve disk 12 extends across the bore of the branch connection 6, closing the same. When the valve stem is rotated, the valve is opened until the stop 17 engages the shoulder 8, in which position the valve disk will be turned one-quarter of a revolution and the fluid can flow freely through the branch connection 6. As many branch connections and valves of the type described will be employed as there are horns 7.

In convenient position to be operated by the chauffeur, is a key board 20. This key board comprises a U-shaped frame having a base 21 adapted to be secured to the seat or body and a pair of flanges 22. This frame is provided with a shaft 23 on which are pivoted a plurality of key levers corresponding in number to the number of horns or signaling devices. These levers are of the angle type and comprise each a pair of angularly-disposed arms 24 and 25, one of said arms being provided with a key 26 adapted to be engaged by a finger of the operator and the other arm being connected, by means of a wire or other flexible connection 27, with the screw 16 on the corresponding valve-operating disk 14.

28 denotes a cross bar extending across the frame and adapted to limit the movement of the key levers.

With the construction thus far described, the operator will be enabled to play one or more of the horns 7 at will to produce a signal or a chord, or, if desirable, to play a musical selection.

It is often desirable to mechanically operate a plurality of horns in unison, to produce a chord or a signal composed of a plurality of individual notes. To enable the operator to secure this result, I provide a shaft 29 having a plurality of projections thereon and adapted to engage the lever arms 25 and operate different combinations of said lever arms and of the horns, according to the position to which the shaft may be rotated. In the drawing I have shown the shaft 29 as provided with three sets of projections, each set being in a common plane extending radially from the shaft center. One such set of projections is shown at 30, another set at 31, and a third set at 32. In the exemplification of my invention as shown herein, each set comprises three projections, but it will be understood that the number of projections constituting a set and the number of such sets may be varied, according to the number of horns or signaling devices employed. One end of the shaft 29 projects through a sleeve 33 having therein

a plurality of notches and the other end projects through the opposite end of the frame and is provided at its outermost portion with a disk 34 forming a bearing for one end of a spiral spring 35 the other end of which bears against the side member of the frame 21 and tends to force the shaft through such end of the frame. The end of the shaft opposite the disk 34 is provided with an arm 36 projecting at right angles therefrom and with an operating handle 37. The arm 36 is adapted to engage a plurality of notches in the outer end of the sleeve 33. In the position shown in Fig. 2, the arm 36 is in a notch corresponding to the "dead" or neutral condition of the horns. When moved into the notch 38, the projections 30 are brought into engagement with the corresponding arms 25, as shown in Fig. 3, and a suitable group of horns is operated to produce a chord or a signal. When moved into the notches 39 and 40, the projections 31 and 32, respectively, will be brought into engagement with appropriate lever arms 25. The arm 36 will be retained in the notches by the action of the spring 35. To facilitate the passage of the arm 36 over the projections 41 between the notches, the opposite sides of each projection are beveled, as shown at 42.

It will be possible for the operator to sound the horns or signaling devices one at a time, or in groups or combinations, by means of the keys 26. Should he desire, however, to give a signal from a plurality of horns or signaling devices sounding in unison, he can do so by operating the handle 37. By rotating the shaft 29, a plurality of such combined signals or chords may be given in succession. On releasing the keys 26 or the arms 25, the springs 19 will close the valves 12 and return the key lever to the position shown in Fig. 2.

It will be understood that, in operation, the cut-out valve will be first operated, as by the lever 43 to cut out the exhaust from the pipe 4^a and divert it into the pipe 4. No sound will be produced, however, unless one or more of the valves in the branch connections 6 are opened.

The pin or screw 16 is soldered into its aperture. In order to secure a proper lead of the wire from a disk to its key, the disk may be adjusted by merely removing the screw 18 and inserting it through an aperture in the disk which will secure the proper lead from pin 16 to the key.

Having thus described my invention, what I claim is:

1. In mechanism of the character set forth, the combination of a plurality of fluid pressure operated members, a rotary valve for controlling the supply of pressure fluid to each of said members, stops arranged to limit the movement of each of

said valves, a spring tending to hold each of said valves in closed position, a plurality of keys, a flexible device extending between each of said keys and a valve, and means whereby each device may be adjustably connected to its valve to vary the lead of said device from the valve.

2. In mechanism of the character set forth, the combination of a plurality of fluid pressure operated members, a rotary valve controlling the flow of fluid to each member, said valve comprising a stem having a disk thereon, a plurality of keys, a flexible operating device extending from each key, and means whereby each of said devices may be connected to a disk at different points thereof.

3. In mechanism of the character set forth, the combination of a fluid pressure operated member, a valve controlling the flow of pressure fluid to said member, said valve comprising a stem having a disk thereon, said disk being provided with a plurality of apertures, a pin adapted to be inserted into any of said apertures, and an operating device connected to said pin.

4. In mechanism of the character set forth, the combination, with a fluid pressure operated member, of a connection for supplying pressure fluid thereto, a rotary valve in said connection, said valve having a stem extending through the casing of the connection, a pair of stop shoulders carried by said connection, a stop carried by the stem, and a spring surrounding said stem and having one end secured to one of the shoulders of the connection and the other end secured to the stop carried by the valve stem.

5. In mechanism of the character set forth, the combination of a fluid pressure

supply pipe, a plurality of branches connected therewith, a rotary valve mounted in each branch, a keyboard comprising a plurality of keys, a flexible device extending between each key and a valve, and means whereby the point of connection between each of said flexible devices and its valve may be adjusted.

6. In a mechanism of the character set forth, the combination of a plurality of fluid pressure operated members, valves each rotatable about an axis and each adapted to control the supply of pressure fluid to one of said members, means normally closing each of said valves, a keyboard comprising a plurality of keys, a flexible device extending between each key and a valve, and means whereby the point of connection between each of said flexible devices and its valve may be angularly adjusted.

7. In a mechanism of the character set forth, the combination of a plurality of fluid pressure operated members, a valve for controlling the supply of pressure fluid to each of said members, means tending to hold each of said valves in closed position, a keyboard comprising a plurality of keys, a flexible device connected to each of said keys, and an angularly adjustable device connected to each valve and to one of said flexible devices.

In testimony whereof, I hereunto affix my signature in the presence of two witnesses,

CLAUD H. FOSTER.
